United States Patent Office

Des. 211,576
Patented July 2, 1968

211,576

FAN ORIFICE ENCLOSURE

Louis J. Jenn and Thomas R. Field, Indianapolis, Ind.,
assignors to Jenn-Air Corporation, Indianapolis, Ind.,
a corporation of Indiana

Filed Sept. 28, 1967, Ser. No. 8,776

Term of patent 14 years

(Cl. D23—155)

Fig. 1.

Fig. 2.

Fig. 3.

FIGURE 1 is a perspective of the front of a fan orifice enclosure embodying the new design;

FIG. 2 is a vertical section of the enclosure shown in FIG. 1; and

FIG. 3 is a perspective of the rear of the enclosure shown in FIG. 1.

The dominant features of our new design reside in the portions shown in full lines.

We claim:

The ornamental design for a fan orifice enclosure, substantially as shown and described.
